ANTIFRICTION BEARING

Filed Jan. 2, 1924

Inventor
Hubert M. Perry
by Clara E. McElroy Atty.

UNITED STATES PATENT OFFICE.

HUBERT M. PERRY, OF CHICAGO, ILLINOIS, ASSIGNOR TO SOPHIE L. WOODS, OF CHICAGO, ILLINOIS.

ANTIFRICTION BEARING.

Application filed January 2, 1924. Serial No. 683,913.

This invention relates to improvements in antifriction bearings for railroad cars and more particularly to a side bearing carried upon the truck bolster of the car as distinguished from one carried by the body bolster of the car.

The invention consists of the matters hereinafter described and more particularly pointed out in the appended claim.

10 In the drawings:—

Fig. 1 is a view in plan elevation of a side bearing embodying my invention, parts thereof being broken away to more clearly illustrate the interior construction.

15 Fig. 2 is a longitudinal, vertical central section through the side bearing on an enlarged scale, the plane of the section being indicated by the line 2—2 of Fig. 1.

Fig. 3 is a view similar to Fig. 2, with 20 the roller shown at one limit of its movement in the casing.

Fig. 4 is a transverse vertical section through the side bearing on the line 4—4 of Fig. 2.

25 Referring now in detail to that embodiment of the invention illustrated in the accompanying drawings:—10 indicates the casing of the side bearing which contains the antifriction element. Said casing consists 30 of a rectangular shell, open top and bottom, and having upright side walls 11, 11 and upright end walls 12, 12. The casing is provided at its bottom with laterally extending ears 13, 13 by means of which it is 35 attached to a truck bolster of a railroad car, indicated by the line 14 in Fig. 2.

15, 15 indicate upwardly inclined flanges which extend inwardly from the bottom ends of the end walls 12 to provide parts of 40 the bottom wall of the casing. Said flanges terminate in depending ribs 16, each of which includes a downwardly facing shoulder 16^a. The bottom edges of the side walls 11, 11 and the depending ribs 16 below the 45 shoulders 16^a define a rectangular opening in which is fixed a bottom filler plate or block 17. The top surface 17^a of said filler plate is flat and said plate engages at its ends against the shoulders 16^a, and is locked in position by bending in the bottom ends 50 of the ribs 16, as shown in Fig. 2. Upon said flat top surface of the filler plate rests a bearing or wear plate 18 which is curved upwardly towards its ends, so as to be capa-

ble of a longitudinal or endwise rocking movement upon said filler plate. The inner vertical ends of the flanges 15 above the shoulders 16^a provide stops 15^a which prevent endwise sliding or translation of the rocking bearing plate upon the filler plate. 55 On the end walls 11 of the casing are provided longitudinally spaced, downwardly facing shoulders 19 which overhang the side margins of the bearing plate and are spaced at different heights above the filler plate 60 to limit the rocking movement of said bearing plate. The ribs 16 are made parallel with the end walls 12 of the casing in the first instance, but after the antifriction element and the plates 17, 18 have been assembled in the casing, said ribs are bent inwardly to retain both of said plates within the casing.

20 indicates an antifriction element or roller which is located within the casing and 75 is adapted to roll longitudinally on the bearing or wear plate 18 for a limited distance from the center of the casing toward each end thereof in a familiar manner. Said antifriction roller is provided at its ends 80 with coaxial trunnions 21 which extend into but are free from engagement with the top and bottom parts of longitudinal grooves 22, 22 formed in the side walls of the casing above the ribs which include the shoulders 19 before referred to. The longitudinal grooves 22 have rounded ends 23, 23 made on a radius greater than that of the trunnions 21 of the roller.

24 indicates a vertically disposed groove 90 formed on the inner surface of each side wall, and which opens through the bottom of the casing and into each groove 22, midway between its ends 23. At the corners of the casing,—that is to say at the junction of the side walls and end walls 11 and 12 respectively, there are provided arcuate shoulders 25, 25 which face inwardly toward each other from the end walls of the casing. The arcuate surface 26 of each of said shoulders 95 is made on a radius corresponding to that of the periphery of the roller and said surfaces are so correlated with respect to the ends 23 of the grooves 22 that the periphery of the roller and said trunnions will 100 simultaneously engage with said arcuate shoulders and the ends of said grooves respectively, to arrest the rolling movement of 105

the roller upon the wear plate. By this construction, both a trunnion stop and a body stop is provided for the roller at the ends of its rolling movement in the casing. 5 The trunnions will engage said ends at the horizontal middle thereof but will be free from the top and bottom parts of said ends. It is to be noted that there is no possibility of any bearing engagement of the trunnions 10 against the bottom part of said grooves, so that the roller can never rotate upon the trunnions as axles, but the load is transmitted at all times through the body of the roller and never in any manner through the 15 trunnions. In that part of the end walls 12 above the flanges 15 are provided ventilation openings 27 through which cinders and the like may escape from the interior of the casing.

20 The operation of the bearing is apparent from the description set forth. When not under load, the roller will naturally assume a central position in the casing, as shown in Fig. 1. When the roller is engaged by the bearing plate on the body bolster (not shown) and is caused to roll toward one end of the casing into that position shown in Fig. 3, the bearing or wear plate will rock endwise upon the filler block 25 into the position shown in Fig. 3, and the trunnions 21 and the periphery of the roller 20 will simultaneously engage the ends 28 of the grooves 22 and the curved surface 26 of the shoulders 25 respectively, as shown 30 in Fig. 3. Upon release of the load imparted to the roller by the body bolster, the rocking bearing plate will assume its normal position upon the filler plate and said roller will roll toward the center of the casing to the position shown in full lines in Fig. 2. It is to be noted that when the bearing plate has rocked to the position shown 35 in Fig. 3, its higher or left hand end is still in a position to engage the flanges 15 above the shoulders 16^a so that even under a shock or jar to the car, there can be no translation of the wear plate. This construction eliminates the provision of extraneous coacting means on the bearing and filler plates to prevent such translation, and thus 40 materially reduces the cost of production.

Another advantage in the construction before described is that there is no elevating

of the car body when the same is taking a curve in a track.

55 Before the plates 17 and 18 are assembled into the casing, the roller 20 is inserted through the opening in the bottom of the casing occupied by said plates, the trunnions 21, 21 entering the grooves 22 through 60 the vertical branches or parts 24 thereof. After the roller is in position the plates are locked in the casing as before described, so that the entire side bearing may be shipped fully assembled to the place of installation 65 upon the cars, it being impossible for the roller to be withdrawn through the top of the casing because of the engagement of the trunnions in the grooves 22.

70 While in describing my invention I have referred to certain details of mechanical construction and arrangement of parts, I do not wish to be limited thereto except as may be pointed out in the appended claim.

75 I claim as my invention:

In an antifriction bearing of the kind described, the combination of an open top casing having sides, ends and a bottom wall which bottom wall has an opening therein, a filler block in said opening and having a 80 flat top bearing surface, a longitudinally curved bearing plate engaged and capable of a longitudinal rocking movement upon said filler-block, each side wall of the casing having a longitudinally extending 85 groove therein, there being shoulders provided on said side walls below said grooves which overhang the side margins of the bearing plate to be engaged thereby when said bearing plate is rocked upon the filler-block, and a roller in said casing capable of a rolling movement on said bearing plate from the center toward either end of the casing, said roller having end trunnions which extend into but are free from engagement 90 with the top and bottom walls of said longitudinal grooves, there being parts of the casing extending above the filler block to be engaged by the end of the rocking plate and to arrest the endwise movement there- 95 of upon the filler block.

100 In testimony that I claim the foregoing as my invention, I affix my signature, this 28th day of November, A. D. 1923.

HUBERT M. PERRY.
